FEELER-MOTION FOR LOOMS.

1,313,349.

Specification of Letters Patent. Patented Aug. 19, 1919.

Application filed January 3, 1916. Serial No. 69,739.

To all whom it may concern:

Be it known that I, EDWARD S. STIMPSON, a citizen of the United States, residing at Hopedale, in the county of Worcester and

5 State of Massachusetts, have invented an Improvement in Feeler-Motions for Looms, of which the following description, in connection with the accompanying drawings, is a specification, like characters on the drawings representing like parts.

10 The invention to be hereinafter described relates to feeler motions for looms, and more particularly to feeler motions of that type wherein, upon substantial exhaustion of the filling in the shuttle, the feeler is moved in a direction longitudinally of the shuttle or filling carrier to place a train of mechanism in operative condition for effecting replenishment of the filling or otherwise changing the loom operation.

20 Such replenishment of filling may be effected either by changing the shuttle containing the substantially-exhausted filling for another provided with a working supply, or by changing the filling carrier or bobbin in the shuttle for one provided with a fresh supply of filling; and while either of these systems of replenishment may be employed in connection with the present invention, the following description will refer more particularly to the invention as associated with that system wherein the filling carrier or bobbin is changed in the shuttle.

25 In the general class of feeler motions referred to, the feeler is usually provided with an end portion adapted to enter the shuttle on each detecting beat of the lay and be prevented from movement in a direction longitudinally of the shuttle or filling carrier by engagement with the wound mass of filling when a working supply is present, but when the filling is substantially exhausted and is no longer capable of resisting the tendency of the feeler to move longitudinally of the shuttle, the feeler is permitted to move in said direction to thereby cause a train of mechanism to become effective to replenish the filling. Where the feeler is of that type wherein means other than the forward pressure of the filling carrier is employed to impart to the feeler its movement longitudinally of the shuttle, it is necessary after the feeler has been given its longitudinal movement and replenishment of filling has been effected, to return it to its ini-

tial or feeling position against the action of said means, that it may thereafter perform its function in relation to the fresh supply of filling.

On each detecting beat the feeler should be held from movement responsive to the means for moving it in a direction longitudinally of the shuttle, until the critical point in the beat-up movement of the lay is reached, that is, until in the forward movement of the lay, the end of the feeler has engaged the filling on the bobbin or carrier, and at such time the feeler should be set free to respond to said moving means in case the filling has become substantially exhausted. As the lay moves back, after a detecting action by the feeler, the feeler again should be locked from movement responsive to its moving means.

An important feature of the present invention, therefore, consists of means coöperating with a moving part of the loom for returning the feeler to proper feeling position after a replenishing operation, and acting on each detecting beat to prevent movement of the feeler in a direction longitudinally of the shuttle after the critical point of the feeler detection has been passed, and as the lay moves back, if the feeler has not detected substantial exhaustion of filling. This feature of the invention may be carried into effect by means coöperating with the weft hammer or other operating element to prevent movement of the feeler longitudinally of the shuttle if such movement of the feeler has been previously prevented by the mass of filling in the shuttle during the feeling action of the feeler as the lay beats up.

It is frequently desirable to operate the loom without laying filling in the shed. In such case it is usual to remove the shuttle from the loom. Under such conditions, the feeler will not, of course, contact with the filling on the detecting beat of the lay, and will consequently be moved longitudinally of the shuttle and effect actuation of the filling replenishing mechanism at a time when replenishment is not desired or required. Another important feature of the present invention, therefore, consists in means positioned at the will of the operator or attendant for locking or holding the feeler from movement in a direction longitudinally of the shuttle when the loom is

being operated without filling or without the shuttle. When the filling carrier or shuttle is returned to the loom, it is important that the feeler should at once become effective to indicate the condition of the filling; and to this end another feature of the invention consists in automatically freeing the feeler from said holding means when the loom is operated with the filling carrier present.

10 Other features of the invention and combination of parts comprised thereunder will be hereinafter described and the invention will be definitely set forth by the claims.

In the drawings:

15 Figure 1 is a plan view showing sufficient parts of the loom frame and loom elements to make clear the construction and operation of the present invention;

20 Fig. 2 is a section on the line 2—2 of Fig. 1;

25 Fig. 3 is a section on the line 3—3 of Fig. 1;

Fig. 4 is an enlarged detail partly in section, and showing more particularly the relation of the weft hammer or other operating element and the end of the swing arm or controller;

30 Fig. 5 is a detached detail showing the feeler in locked position and the relation of feeler parts when the loom is to be run without filling; and

Fig. 6 is a perspective showing the end of the swing arm or controller and its slide, some of the parts being broken away.

35 The feeler motion constituting the present invention is especially adapted for use in connection with automatic looms wherein, upon substantial exhaustion of the filling in the shuttle, a new supply of filling is furnished, but obviously, the invention may be employed in connection with some other train of mechanism.

40 The feeler constituting an element of the present invention is of that character which, upon substantial exhaustion of the filling in the shuttle, may be moved longitudinally of the shuttle to initiate the replenishing operation. In the illustrated form of the invention, the feeler comprises the part 1 carrying

45 the feeler member 2 which, on each detecting beat, enters through a slot in the shuttle-box as usual, and through a slot 3 in the side of the shuttle 4 and feels for the condition of the filling on the bobbin or carrier 5 within the shuttle. The part 1 of the feeler is preferably pivoted at 6 to a stand 7 secured to the loom frame or breast beam 9, and while this pivotal connection is well suited for the intended purpose, it is within the

55 purview of the present invention that the feeler may be otherwise mounted for movement in a direction longitudinally of the shuttle.

60 The part 1 of the feeler is provided with the bridge portions 10 and 11 which may be

appropriately formed either by turning up portions of the part 1 or otherwise, and each of said bridges 10 and 11 is provided with an opening through which passes the feeler member 2. The feeler member 2 is normally held in projected position as indicated in Fig. 5 by a spring 12, one end of which rests against the bridge 11 and the other against the stop shoulders 13 of the feeler member 2, the construction being such that the feeler member 2 will be normally forced yieldingly toward the lay with the shouldered portions 13 in contact with the bridge 10. The feeling end of the feeler member 2 is provided with the teeth or roughened end 14, the construction being such that the roughened or toothed end 14 of the feeler member 2 will engage the filling mass within the shuttle on each detecting beat and prevent movement of the feeler longitudinally of the shuttle, should a working supply of filling be present, but permit such movement of the feeler longitudinally of the shuttle, should the filling be substantially exhausted.

65 In order that the stand 7 may be adjustably connected to the bracket 8, the said stand is provided with the slot 15 through which passes the bolt 16 for adjustably holding the stand 7 in desired position. On each detecting beat of the lay, the feeler member 2 will engage the filling mass or the bobbin itself in case the filling has become substantially exhausted and will be moved toward the front as indicated in Fig. 1, against the tension of the spring 12.

70 Extending transversely of the loom is the usual transverse or change shaft 17 which is suitably associated with a train of mechanism for effecting filling replenishment when said transverse or change shaft 17 has a rocking movement imparted thereto, as will presently appear. The filling replenishing mechanism, as well as the train of the connecting parts between the transverse or change shaft 17 and such mechanism are not herein shown and described, because their particulars of structure form no essential part of the present invention and are well understood by those skilled in the art.

75 Secured to the shaft 17 is the arm 18 extending upward therefrom and having operatively connected thereto at 19, the arm 20. If the arm 20 is moved forward or to the right, Fig. 3, it will cause rocking movement to be imparted to the shaft 17 and through the train of mechanism hereinbefore referred to, effect initiation of filling replenishment. Since movement of the arm 20 initiates replenishment, it will hereinafter be termed the "actuator," for identification, but such term is one of identification simply, and not one of limitation.

80 It is the purpose of the present invention that the feeler shall be under the control of means tending to move it longitudinally of

90

the shuttle, so that upon substantial exhaustion of the filling on the detecting beat, such longitudinal movement of the feeler may take place and effect filling replenishment. As one form of means for thus acting upon the feeler, the present embodiment of the invention shows a swing arm or controller 21, Figs. 1 and 4, pivotally connected to the actuator 20, said swing arm or controller being normally under the influence of a spring for moving or swinging said arm or controller in a direction to cause movement of the feeler longitudinally of the shuttle through the interposed connections, as will presently appear.

In the present instance, the swing arm or controller 21 is pivotally connected to the actuator 20 by a pin 22 extending upward from the actuator 20. A spring 23 surrounds the pin 21, one end of the said spring being connected to a cap-piece 24 secured by a pin 25 to the pivotal pin 22, and the other end of said spring being connected at 26 to the swing arm or controller 21, the construction being such that the said spring 23 normally acts to turn the swing arm contraclockwise, viewing Fig. 4, or in a direction to impart movement of the feeler longitudinally of the shuttle through interposed connections to be described. In order that the swing arm 21 may be limited in its movement under the impulse of the spring 23, a suitable limiting stop 27 is extended from the actuator 20 and adapted to be engaged by a shouldered portion 28 of the swing arm or controller, as indicated in Fig. 4.

The feeler is connected to the swing arm or controller so that the feeler and swing arm or controller move in unison. As a convenient means for effecting this connection, the part 1 of the feeler and the swing arm or controller are each provided with a flange or projection 29 having suitable holes or openings 30 for engagement by the end portions of the connector 31 which, as illustrated in Fig. 2, is preferably formed as a rod and is made adjustable in length by the turn-buckle 32, the construction being such that should the swing arm or controller move upon its pivotal mounting 22, such movement will be imparted to the feeler and cause it to be moved in a direction longitudinally of the shuttle.

As hereinbefore noted, the present invention provides means for preventing movement of the feeler in a direction longitudinally of the shuttle after the critical point of feeler action is passed, should the feeler have found a working supply of filling present in the shuttle on its feeling action. Should the feeler have detected a substantial exhaustion of filling in the shuttle, however, and have in consequence, been moved by the swing arm or controller in a direction longitudinally of the shuttle, the invention

further contemplates the provision of means for returning the feeler to its feeling position prior to the next detecting beat.

The swing arm or controller 21 in the present instance of the invention is provided with a slotted end portion 33, Fig. 4, in which is movably mounted the slide 34. A suitable stop or pin 35 may be employed for limiting the slide in the slotted end of the swing arm or controller, and in order that said slide may not move too freely, a spring finger 36 secured at 37 to the swing arm or controller has its end 38 extended through an opening in the side wall of the swing arm or controller to bear against the side portion of the slide 33, the construction being such that while the slide 34 may move longitudinally with relation to the swing arm or controller, accidental or undesired movement thereof will be prevented by the limiting effect of the spring finger 36.

The slide 34 is provided with an incline shouldered portion 39, Fig. 4, and a socketed portion 40 for a purpose that will presently appear. The swing arm or controller 21 has a lug 41 which, when the filling in the shuttle has become substantially exhausted, may be moved by the swing arm or controller into the path of an operating part 42. The part 42 may be appropriately connected to some moving element of the loom, and in the present instance of the invention it is shown as connected by a finger or arm 43 to the weft hammer 44, only a portion of which is indicated in Fig. 3. At one side of the lug 41 of the swing arm or controller is a slot 45 adapted to be engaged by the operating part 42 provided the swing arm or controller is prevented from moving laterally under the impulse of its spring 23 by reason of the engagement of the feeler with a working supply of filling in the shuttle on the detecting movement of the lay; and as the lay moves back after the detecting action of the feeler has been completed, the operating part 42 still engaging the slot 45 of the swing arm or controller will prevent movement of the swing arm or controller under the impulse of its actuating spring 23. As the operating part 42 moves forward, Fig. 4, and engages the slot 45 in the swing arm or controller, it meets the edge portion 46 of the slotted slide 34 and, perforce, moves the slotted slide 34 with it as it progresses toward the front portion of the slot 45. As the operating part 42 moves rearwardly and approaches the outer portion of the slot 45, it finds the slot 40 of the slide in position to be engaged by the rearwardly moving part 42, so that as the part 42 continues rearwardly to complete its rearward movement, it carries the slide 34 with it and, being engaged with the slot 40 of the slide 34, prevents movement of the swing arm or controller under the im-

4
pulse of its actuating spring 23. Should the feeler have found a condition of substantial exhaustion of the filling in the shuttle, then, as the operating part 42 moves 5 forward, the feeler would not be prevented from movement longitudinally of the shuttle owing to the absence of sufficient filling in the shuttle, and the swing arm or controller 21 will thereupon respond to the demands of 10 its spring 23 as the operating part 42 moves forward, Fig. 4, out of the slot or recess 40 of the slide, and the lug 41 will be placed in the path of the operating part 42, thereby causing the actuator 20 to be moved front- 15 ward to initiate filling replenishment. Filling replenishment having been effected and the operating part 42 being moved rear- 20 wardly, it first strikes the incline portion 39 of the slide 34, thereby swinging the swing arm or controller 21 clockwise, viewing Fig. 4, until the operating part 42 engages the slot 40 of the slide and at the same time draws the feeler into its proper feeling position prior to the next detecting 25 movement of the lay.

As hereinbefore indicated, it is sometimes desirable to run the loom without laying the filling in the shed or without the filling carrier or shuttle, and in such case, if means 30 are not provided to prevent movement of the feeler longitudinally of the lay, the swing arm or controller will move the feeler in such direction as soon as the operating part 42 has disengaged the slotted portion 35 40 of the slide 34 and thereby position the lug 41 for engagement by the operating part 42 and effect filling replenishment. Filling replenishment, however, is not desired at this time, and the present invention, there- 40 fore, contemplates means controllable at the will of the operator for preventing longitudi- 45 nal movement of the feeler when the loom is being run without laying the filling, or when the shuttle is absent therefrom. As before noted, also, it is desirable that when the shuttle is returned to the loom or the filling carrier is placed in the loom, on the following detecting beat, the feeler should be released from its locked position and the 50 present invention, therefore, contemplates that on such first detecting movement after the shuttle or filling carrier has been returned to the loom, the feeler shall be automatically released, so that thereafter it may 55 move longitudinally of the shuttle whenever the filling supply has become substantially exhausted.

In the present form of the invention, there is pivotally mounted at 47, Figs. 1 60 and 5, a catch 48 having a shouldered part 49 adapted to engage the feeler to prevent longitudinal movement of the feeler, substantially as indicated in Fig. 5. In the present instance the shouldered portion 49 65 of the catch 48 is adapted to engage the

bridge 11 of the feeler part 1, but obviously the catch may be variously contrived to engage any suitable portion of the feeler part 1 to effect its locking function. When the catch 48 has been moved into its locking or 70 holding position and the loom is operated without filling, the feeler member 2 will not be moved forward on the detecting movement of the lay, and since the feeler cannot move longitudinally of the shuttle by reason of the operative position of the catch 48, the swing arm or controller 21 will also be locked, the construction being such that under the conditions described, the operating part 42 will move forward, without 75 engaging the projection 41 of the swing arm or controller and the loom will continue to run without effecting filling replenishment. 80

In order that the catch 48 or other means employed for locking the feeler as described 85 may be automatically thrown out of locking position when the filling carrier or shuttle is returned to the loom, the catch may be provided with the part to be operated by the feeler member 2, as the latter moves 90 frontward during the beat-up. In the present instance the catch 48 is provided with a projecting finger 50, Fig. 5, which is extended into the path of the outer end portion of the feeler member 2, so that as the 95 feeler member 2 moves frontwardly under impact of the filling mass in the shuttle, or the filling carrier, the catch 48 will be tripped or thrown into inoperative position as indicated in Fig. 1. 100

The actuator 20 is movable toward and from the front of the loom, and may be appropriately supported for this movement by having its inner portion resting upon a suitable under guide and against a side guiding element, but this feature of the construction and its details may be varied between wide limits and forms no essential feature of the invention. 105

Various changes may be made in the particulars of structure which is herein illustrative of one embodiment of the present invention, and still be within the scope of the invention. 110

What is claimed is:—

1. In a feeler motion for looms, the combination of an operating member movable toward and from the front of the loom, a controller, means normally acting to move the controller into operative relation with the operating member, a feeler connected to the controller and held from movement in a direction longitudinally of the shuttle by engagement with the filling as the lay beats up until the filling is substantially exhausted, and a slide on the controller adapted to engage the operating member on the backward movement thereof to prevent movement of the feeler from feeling position as the lay moves back. 125 130

2. In a feeler motion for looms, the combination of an operating member, a controller, means normally tending to relatively move the controller and member into operative relation, said controller carrying a slide adapted to engage said operating member and prevent movement of the controller into operative relation with said member until said member has started on its operating 5 stroke and then to be disengaged therefrom to permit movement of the controller into operative relation with said member, a feeler connected to the controller and held from movement longitudinally of the shuttle by 10 engagement with the filling when a working supply is present to prevent movement of the controller into operative relation with the operating member when freed from engagement with the slide.

20 3. In a feeler motion for looms, the combination of an operating member, a controller, means normally acting upon the controller tending to move it into operative relation to the operating member, a slide movable 15 relatively to the controller and acting through engagement with the actuating member to prevent movement of the controller into operative relation with said member during part of the movement of 25 said member, and a feeler connected to the controller and acting by contact with the filling when a working supply is present to prevent movement of the controller into operative relation with the said member during another part of the movement of 30 said member.

4. In a feeler motion for looms, the combination of an operating member, a controller, means normally acting to move the controller into operative relation with the operating member, and means movable with and relatively to the controller and coöperating with the operating member to prevent movement of the controller in response to 40 said normally acting means during part of the movement of the operating member.

5. In a feeler motion for looms, the combination of an operating member, a controller, means normally acting to move the controller into operative relation with the operating member, means movable with and relatively to the controller coöperating with the operating member to prevent movement of the controller in response to said normally 50 acting means during part of the movement of the operating member, and a feeler connected to the controller and acting by contact with the filling when a working supply is present in the shuttle to prevent movement of the controller in response to its 55 normally acting means during the remainder of the movement of the operating member.

6. A feeler motion for looms, comprising 60 a feeler to feel for the filling in the shuttle,

a controller connected to the feeler, means acting to move the feeler in a direction longitudinally of the shuttle when the filling is substantially exhausted, an operating member, a device mounted on and movable 70 relatively to the controller and having a part adapted to be engaged by the operating member on its backward movement to restore the feeler to feeling position after a call for filling replenishment. 75

7. In a feeler motion for looms, the combination of a feeler for detecting the condition of the filling in the shuttle, means normally acting to move the feeler longitudinally of the shuttle as it performs its feeling function, said feeler being prevented from responding to said means by the filling in the shuttle until it has become substantially exhausted, and means rendered effective at will to prevent feeler movement in a 80 direction longitudinally of the shuttle.

8. In a feeler motion for looms, the combination of a feeler for detecting the condition of the filling in the shuttle and movable 85 frontward thereby, means normally acting upon the feeler as it performs its feeling function and tending to move the feeler in a direction longitudinally of the shuttle, said feeler being prevented from such longitudinal movement by the filling in the shuttle until it has become substantially exhausted, and manually controlled means rendered effective 90 at will for locking the feeler from such longitudinal movement when the loom is being run without the shuttle and adapted to be automatically actuated to unlock the feeler when the shuttle is restored. 95

9. In a feeler motion for looms, the combination of a feeler adapted to feel for the filling in the shuttle as the lay beats up, means 100 for moving it in a direction longitudinally of the shuttle when a working supply of filling is not presented to the feeler, and manually positioned means for holding the feeler from such longitudinal movement when the loom 105 is run without the shuttle, said feeler being automatically freed from said manually positioned holding means when the shuttle is restored and the loom operated. 110

10. In a feeler motion for looms, the combination of a feeler mounted for movement longitudinally of the shuttle, means for moving the feeler longitudinally of the shuttle to initiate filling replenishment when a working supply of filling fails to be presented to the feeler as the lay beats up, means 115 manually positioned to prevent initiation of filling replenishment when the loom is operated without a filling carrier to enable the loom to be run without laying filling in 120 the shed, said manually positioned means becoming automatically ineffective when the loom is run with a filling carrier. 125

11. In a feeler motion for looms, the combination of a pivotally mounted feeler 130

adapted to feel for the filling in the shuttle, means tending to swing the feeler in a direction longitudinally of the shuttle when the feeler performs its feeling function and effecting such longitudinal movement when the filling has become substantially exhausted, a device manually movable at will to prevent such longitudinal swinging movement of the feeler when a filling carrier is not presented to the feeler as the lay beats up, said device becoming automatically ineffective when the loom is run with a filling carrier present.

12. In a feeler motion for looms, the combination of a feeler comprising a feeler member adapted to be moved forward by the filling carrier in the shuttle as the lay beats up, means for moving it longitudinally of the shuttle when a working supply of filling fails to be presented thereto, a catch for preventing such longitudinal movement of the feeler when a filling carrier fails to be presented to the feeler member, and a part connected to said catch to be engaged by the feeler member as the lay beats up with a filling carrier in the shuttle to free the feeler from control of the catch.

13. In a feeler motion for looms, a feeler adapted to feel for the filling in the shuttle, means for moving it longitudinally of the shuttle when the filling has become substantially exhausted or the loom is run without a filling carrier, means for initiating filling replenishment and a catch movable at will into position to hold the feeler from such longitudinal movement.

14. In a feeler motion for looms, the combination of a feeler, means for moving the feeler longitudinally of the shuttle when the filling is substantially exhausted, an operating member, a controller, relative position-determining means between the operating member and controller including a slide, and means for restraining too free movement of the slide.

15. In a feeler motion for looms, the combination of a feeler, means for moving the feeler longitudinally of the shuttle when the filling is substantially exhausted, an operating member, a controller, relative position-determining means between the operating member and controller including a slide movable relative to the operating member and controller.

16. In a feeler motion for looms, the combination of a feeler, means for moving the feeler longitudinally of the shuttle when the filling is substantially exhausted, an

operating member, a controller, and relative position-determining means between the operating member and controller including a slide mounted on the controller and having engaging portions by which it may be moved by the operating member.

17. In a feeler motion for looms, the combination of a feeler, means for moving the feeler longitudinally of the shuttle when the filling is substantially exhausted, an operating member, a controller, and relative position-determining means between the operating member and controller including a slide mounted on the controller and having a slotted portion to permit movement of the controller and operating member into operative relation, and another portion to lock the operating member and controller from movement into operative relation.

18. A feeler mechanism for looms, comprising a feeler, means for moving the feeler longitudinally of the shuttle when it fails to be engaged by a working supply of filling on a detecting beat, and means for locking the feeler from such movement when the loom is being run without filling.

19. A feeler mechanism for looms, comprising, in combination, a feeler, means for moving the feeler longitudinally of the shuttle to effect initiation of filling replenishment, a locking catch for locking the feeler from such longitudinal movement when the loom is run without filling, and an unlocking finger for tripping the catch and unlocking the feeler when the loom is run with filling present.

20. A feeler mechanism for looms, comprising, in combination, a feeler, means for moving the feeler longitudinally of the shuttle to effect initiation of filling replenishment, a locking catch having a shoulder for locking the feeler from such longitudinal movement, and means for automatically tripping the catch when the loom is run with filling present.

21. In a feeler motion for looms, the combination of a feeler movable longitudinally of the shuttle and held from such movement by the filling on a detecting beat until substantial exhaustion of filling, and means for locking the feeler from such longitudinal movement when the loom is run without filling.

In testimony whereof I have signed my name to this specification.

EDWARD S. STIMPSON.
